[57] **CLAIM**

The ornamental design for an eyeglass temple, as shown and described.

DESCRIPTION

FIG. 1 is a side elevational view of an eyeglass temple showing our new design, the undisclosed side being a mirror image thereof;

FIG. 2 is an enlarged fragmentary perspective view taken along the lines 2—2 of FIG. 1;

FIG. 3 is a side elevational view of a second embodiment of FIG. 1, the undisclosed side being mirror image thereof; and

FIG. 4 is an enlarged fragmentary perspective view taken along the lines 4—4 of FIG. 3.
